CLAIM

The ornamental design for an underwater vehicle, as shown and described.

DESCRIPTION

FIG. 1 is a top and rear perspective view of an underwater vehicle showing my new design;

FIG. 2 is a top plan view thereof;

FIG. 3 is a right side elevational view thereof, the left side view being a mirror image of that shown;

FIG. 4 is a bottom plan view thereof;

FIG. 5 is a rear elevational view thereof; and

FIG. 6 is a front elevational view thereof.

FIG.1

FIG.5
